US0D1085073S

(12) **United States Design Patent** (10) **Patent No.:** **US D1,085,073 S**
(45) **Date of Patent:** **** Jul. 22, 2025**

(54) **DATA PROCESSING UNIT**

(71) Applicant: **SITA B.V.**, Rotterdam (NL)

(72) Inventors: **Mathieu Eduard Keizer**, Rotterdam (NL); **Swen van Klaarbergen**, Rotterdam (NL); **Bas Bruining**, Eindhoven (NL); **Vincent Laagland**, Eindhoven (NL)

(73) Assignee: **SITA B.V.** (NL)

(**) Term: **15 Years**

(21) Appl. No.: **29/868,756**

(22) Filed: **Dec. 13, 2022**

(30) **Foreign Application Priority Data**

Jun. 13, 2022 (EM) 009060056-0006

(51) **LOC (15) Cl.** **14-02**

(52) **U.S. Cl.**

USPC **D14/307**

(58) **Field of Classification Search**

USPC D10/104.1; D14/322, 336, 371, 373, D14/374, 383, 384, 424, 425, 126, 127, D14/159, 239, 299, 900, 901, 902, 302, D14/303, 304, 305, 306, 307, 308, 311, D14/312, 133; D20/1, 2, 18; D21/324, D21/325, 369, 370

CPC . G07B 15/00; G07C 9/22; G07C 9/25; G07C 9/253; G07C 9/257

(74) *Attorney, Agent, or Firm* — Bradley Arant Boult Cummings LLP; Daniel E. Sineway, Esq.; Adam J. Thompson, Esq.

CLAIM

The ornamental design for a data processing unit as shown and described.

DESCRIPTION

FIG. 1 is a front perspective view of a data processing unit.

FIG. 2 is a back perspective view thereof.

FIG. 3 is a front view thereof.

FIG. 4 is a back view thereof.

FIG. 5 is a top view thereof.

FIG. 6 is a bottom view thereof.

FIG. 7 is a left view thereof; and,

FIG. 8 is a right view thereof.

1 Claim, 8 Drawing Sheets
